UNITED STATES PATENT OFFICE.

HARVEY H. GREENMAN, OF CORTLANDVILLE, NEW YORK.

POSITIVE SHUTTLE-MOTION FOR LOOMS.

SPECIFICATION forming part of Letters Patent No. 291,844, dated January 8, 1884.

Application filed February 14, 1882. (No model.)

To all whom it may concern:

Be it known that I, HARVEY H. GREENMAN, of Cortlandville, in the county of Cortland and State of New York, have invented 5 certain new and useful Improvements in Positive Shuttle-Motions for Looms; and I do hereby declare that the following is a full, clear, and exact description of the invention, which will enable others skilled in the art to which 10 it appertains to make and use the same, reference being had to the accompanying drawings, and to the letters of reference marked thereon, which form a part of this specification.

My invention relates particularly to positive 15 shuttle-motions for looms for weaving textile or other fabrics, and the novelty consists in the construction and arrangement of parts, as will be more fully hereinafter set forth, and specifically pointed out in the claim.

20 The object of the invention is to provide for the proper reciprocation of a shuttle across the loom; and to this end the invention consists, essentially, in the combination, with a shuttle-body and reciprocating carrying-arms, 25 of a movable trigger-frame which operates in guides in the shuttle-body, and which, at each stroke in either direction, first serves to unlock the shuttle at one end from one carrying-arm and then to lock the opposite end to the 30 opposite carrying-arm, both operations being automatic, and both being made with each stroke.

The invention is fully illustrated in the accompanying drawings, which form a part of 35 this specification, and in which—

Figure 1 is a plan view of the shuttle-body and trigger-frame connected thereto; and Fig. 2, a side elevation, partly in section, of the shuttle and its carrying-arms, the shuttle being 40 locked to the left-hand carrying-arm, and the devices in the act of releasing the shuttle from the right-hand carrying-arm, the body of the shuttle and portions of the arms being in elevation.

45 Referring to the drawings, in which similar letters of reference indicate like parts in all the figures, A represents the shuttle-body, having ends or shanks *a*, each of which is provided with a recess, *a'*, having an abrupt or vertical bearing-side, as shown. In a guideway, *b*, formed in the shuttle-body A, operates the trigger-frame B, held in said guide by a screw, *b'*, operating in a slot, *b''*, at each shuttle-shank.

It is not thought necessary to show the carrying-arms and their actuating mechanism in full; but in order that the operation of the devices may be fully understood, reference is made to Patents Nos. 153,693 and 164,924, in which such mechanism is fully illustrated and 60 described. My devices are applicable to either of the actuating devices shown in said patents.

C and C' represent the hollow reciprocating arms, in each of which, at *c*, is secured a spring-catch, D, having hook *d*, and abutting end *d'*, the hook being provided with an incline, *d''*, which operates against a corresponding incline, *a''*, upon the end of each shuttle-shank *a*. The trigger-frame is of such length that when it is moved to one side, so as to cover 65 one of the recesses, *a'*, at the end of its stroke it leaves the other recess open to receive the locking-hook of a carrying-arm. The shuttle being locked to and carried by the reciprocating bar C', the first action of the arm or bar 70 C, as the arms C and C' approach each other, is to have the abutting head *d'* of the spring-catch D in the said arm C to strike against the end of the trigger B and force it over until the opposite end acts against the incline *d''* of 75 the catch D in the arm C', and forces the hook *d* out of the recess *a'* at that end of the shuttle. The continuation of the same stroke locks the arm or bar C to the shuttle, as shown in Fig. 2. On the separating of the arms or bars 80 C and C' the shuttle will then move with the arm or bar C, as will be understood. By this construction and adaptation of the trigger I obviate the necessity of shifting-levers or other mechanism for unlocking the shuttle. 85

Having thus described my invention, what I claim, and desire to secure by Letters Patent of the United States, is—

The shuttle-body A, having recesses *a'*, and the reciprocating arms C C', having spring-catches D, provided with hooks *d d''*, combined with the shifting trigger-frame B, as and for the purposes specified. 95

In testimony that I claim the foregoing as my own I affix my signature in presence of two witnesses.

HARVEY H. GREENMAN.
